(57) **CLAIM**

The ornamental design for a personal digital device hanger, as shown and described.

DESCRIPTION

FIG. 1 is a perspective view of a personal digital device hanger showing my design;

FIG. 2 is a left or right side view thereof;

FIG. 3 is a top side view thereof;

FIG. 4 is a bottom side view thereof;

FIG. 5 is a front side view thereof;

FIG. 6 is a back side view thereof; and,

FIG. 7 is a perspective view of an airline seat tray shown in the upright tray position with the personal digital device positioned thereon the airline seat tray holding the personal digital device.

The broken lines shown in FIGS. 5-7 represent the portions of the design which form no part of the claim.

The disclosure relates generally to ornamental designs for hangers, and more specifically to an ornamental design for a hanger to hold a personal digital device.
